UNITED STATES PATENT OFFICE.

CHRISTOPHER C. SHELBY, OF NEW YORK, N. Y.

STOCKING-SUPPORTER.

SPECIFICATION forming part of Letters Patent No. 267,943, dated November 21, 1882.

Application filed August 11, 1882. (No model.)

To all whom it may concern:

Be it known that I, CHRISTOPHER C. SHELBY, of New York city, county, and State, have invented certain new and useful Improvements in Stocking-Supporters; and I do hereby declare the following to be a full, clear, and exact description of the same, reference being had to the accompanying drawings, forming part of this specification, in which—

10 Figure 1 is a view of a stocking-supporter constructed in accordance with my invention. Fig. 2 is a view of the inner part of the clasp. Fig. 3 is a view of the outer part of the clasp. Fig. 4 is a sectional view taken on the line $x-x$, Fig. 1; and Figs. 5 and 6 are views of modified forms of the clasp.

Similar letters of reference in the several figures denote the same parts.

My invention relates to improvements in 20 stocking-supporters; and it consists in a novel form of clasp employed in connection therewith, constructed as hereinafter described and claimed.

Referring to the drawings, A represents the 25 main webbing of the supporter, preferably elastic webbing, and having secured to its upper end a metallic loop, B, by which to secure the supporter to a button fastened at or near the waist of the wearer, and having preferably connected to its lower end a buckle, C, that can be adjusted up and down when desired.

Suspended from the buckle is the webbing 30 D, to the extremities of which are secured the clasps, each consisting of an inner part, E, having a slot, e, for securing the end of the webbing, and a tongue, e', and an outer plate, F, having a slot, f, for the attachment of the webbing, and an opening, f', for the reception 40 of the tongue e', as will be presently explained.

The webbing D preferably consists of two pieces passed through the loop of the buckle, and connected to each other by stitching or rivets at the points g, so as to leave at each extremity two pieces, d d—one for the attachment of the inner part, E, of the clasp and the other for the attachment of the outer part, F, of the same. This mode of connection enables the webbing to slide freely through the loop of the buckle, and prevents any undue strain upon either of the clasps when the wearer stoops over or otherwise changes position.

The tongue e' of the part E of the clasp has a narrow neck portion, h, that projects at right angles, or nearly so, to the slotted portion e, and at the termination of such neck portion broadens out into a head, i, bent backward at an angle to the neck portion, as shown in Fig. 4.

The opening f' in the part F of the clasp is of triangular form, with rounded corners, as 60 shown in Fig. 3, and is adapted to receive and hold the tongue of the part E.

To secure the clasp to the stocking the part E is inserted between the stocking and the leg of the wearer, and the part F is brought up and 65 the tongue of the part E is pressed through the opening in the part F, carrying with it a portion of the stocking. A slight tension being then put upon the webbing, the stocking is securely held by the clasp, and is not at all 70 liable to accidental displacement, nor will it tear or deface the material of the stocking.

This manner of connecting the supporter to the stocking dispenses with the necessity of sewing buttons on the stocking, and thus saves 75 the wearer much trouble and annoyance.

I preferably strike up each portion of the clasp from a single plate of metal in the form shown in Figs. 2 and 3; but they may be formed of plate metal in the design shown in Fig. 5, 80 or they may be formed of wire, as shown in Fig. 6.

I am aware that prior to my present invention a stocking-supporter clasp has been constructed of an outer plate secured to one piece of webbing, and having an elongated slot widest at the top and narrowest at the bottom, and an inner button or stud secured to another piece of webbing and hanging normally opposite the narrow portion of the slot of the outer 90 plate; but my invention is distinguished from this prior device, in that the opening in the outer plate is of triangular form, widest at the bottom, and the inner part of the clasp consists of a peculiarly curved headed hook, which 95 normally hangs directly opposite the opening in the outer plate. With the prior device to fasten the stocking the inner button or stud is inserted behind the stocking and the outer plate is drawn down until the wide part of the slot comes opposite the loop, when the stud is 100 entered and the outer plate then drawn up to complete the fastening. With my device, however, to secure the stocking, the peculiarly-

shaped headed hook is placed behind the stocking and slightly turned out and made to enter the slot in the outer plate, located exactly opposite it, and then turned up to complete the fastening, no pulling down or up of the supporting-webbings being required.

Having thus described my invention, I claim as new—

The herein-described stocking-supporter to clasps, each consisting of the outer portion, F,

having the triangularly-shaped opening *f'*, widest at its bottom, and the portion E, having the outwardly-bent narrow neck *h* and the backwardly-bent enlarged head *i*, both said parts co-operating to clasp and hold a fabric 15 between them, substantially as described.

CHRISTOPHER C. SHELBY.
